(57) **CLAIM**

The ornamental design for a garlic grinder, as shown and described.

DESCRIPTION

FIG. 1 is a top perspective view of a garlic grinder, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded perspective view of the garlic grinder of FIG. 1;

FIG. 10 is a perspective view of the garlic grinder of FIG. 1 with the bottom element removed to reveal aspects of the design that may not be apparent in other views;

FIG. 11 is a perspective view of the bottom two elements of the garlic grinder of FIG. 1 in an alternative configuration, shown separately to reveal aspects of the design that may not be apparent in other views;

FIG. 12 is a perspective view of the top two elements of the garlic grinder of FIG. 1, shown separately to reveal aspects of the design that may not be apparent in other views; and, FIG. 13 is the 13-13 cross-section of FIG. 3.

The broken lines in the drawings illustrate portions of the garlic grinder that form no part of the claimed design. The claim is directed to the collective appearance of the elements shown.
